COP FRAME

Heinrich Dersen, Krefeld, Germany

Application February 28, 1940, Serial No. 321,263
In Germany December 13, 1938

9 Claims. (Cl. 242—1)

My invention relates to improvements in cop frames, and more particularly in cop frames provided with automatic means for doffing the cops and placing empty cop tubes into winding position. One of the objects of the improvements is to provide a frame in which, during winding, inspection of the cops being formed is not interfered with by the doffing apparatus. Another object of the improvements is to provide a frame in which the said doffing and replenishing apparatus is simple in construction and reliable in operation. With these objects in view, my invention consists in mounting the carrier for the empty cop tubes below the winding position, and providing the same with means for lifting the same with one of the cop tubes into position for being taken up by the means holding the cop tube in winding position, and providing in addition means operative when the said carrier is away from the winding position for receiving the cops when released from the winding position.

Other objects of the improvements will appear from the following description.

For the purpose of explaining the invention an example embodying the same has been shown in the accompanying drawings in which the same reference characters have been used in all the views to indicate corresponding parts.

In said drawings,

Fig. 1 is an elevation partly in section showing a part of the cop frame and the doffing apparatus, the outer end plate of the carrier for the cop tubes being removed.

Fig. 2 is a sectional elevation taken on the line 2—2 of Fig. 1.

Fig. 3 is an elevation partly in section viewed from the left in Fig. 2.

Fig. 4 is a top plan view of the doffing apparatus, and

Fig. 5 is a detail sectional elevation on an enlarged scale showing the doffing apparatus.

The cop frame may have any known or preferred construction, and in the drawings only such parts of the frame have been shown as are necessary for illustrating the cooperation of the doffing apparatus with the winding devices.

In the figures I have shown an upright 1 which is cast integral at its top with a transverse member 2 connecting the same to a similar upright. From the transverse member 2 an arm 3 projects to the right in Fig. 2 which is formed at its end with a downwardly directed portion 4. Further, transverse bars 5 and 6 are secured to the upright 1. On the said frame members the operative parts are supported.

On the transverse member 2 and the downwardly directed portion 4 means are mounted for supporting the cop tube 7 and the cop 8 formed thereon in winding position. Such means are known in the art and I shall briefly describe the same. They consist of a spindle 9 and a counter-punch 10 carried by a slide block 11 acted upon by a spring 12 tending to shift the counter-punch to the left in Fig. 2 and into engagement with the tube 7. The slide block 11 is engaged by an arm 13 connected with suitable operating mechanism for retracting the same from the tube 7 in opposition to the spring 12, for inserting a cop tube 7 or removing the same with the cop formed thereon.

Below the spindle 9 and the counter-punch 10 a device adapted to carry a plurality of cop tubes 7 is mounted which is provided with mechanism for lifting the same with one of the tubes into position between the spindle 9 and the counter-punch 10. As shown, the said carrier consists of two disks 14 and 15 secured by means of screws 16 to a rotary shaft 17, and non-rotatable end plates 18 and 19, the end plate 19 being fixed to a tubular bearing member 20 in which the shaft 17 is rotatable, and the plate 18 being loosely mounted on the shaft 17 and held in position relatively to the plate 19 by means of a rod 21 and arms 22 fixed respectively to the plates 18 and 19. The disks 14 and 15 are provided about their circumferences with cut-out portions 23 in which the tubes 7 are supported near their ends, and the plates 18 and 19 are spaced from the disks 14 and 15 so that they engage the tubes 7 at their opposite ends, and they are also formed with inwardly directed flanges 24, thus holding the tubes 7 in position on the disks 14 and 15.

The tubular bearing member 20 is secured to or made integral with two arms 25 pivotally mounted on an eye 26 provided on the upright 1. The arms 25 are engaged by a rod 27 vertically guided in a bushing 28 fitted in the transverse bar 6. At its bottom end the said rod carries a roller 29 bearing on a cam 30 secured to a shaft 31 mounted in an eye 32 of the upright 1, the said shaft being adapted to be rotated from the source of power that rotates the cop tube when mounted in winding position. Near the rod 27 a set screw 29 is fitted in the transverse bar 6 which is adapted to arrest the bearing member 20 in its lowermost position.

By the mechanism so far described the carrier comprising the disks 14 and 15 and the plates 18 and 19 is adapted to be elevated with the uppermost cop tube 7 into position between

the spindle 9 and the counter-punch 10 as is shown in Fig. 1 in dotted lines, and to be removed therefrom into the position shown in Figs. 1, 2 and 3 in full lines, in which the bearing member 20 rests on the screw 29. To permit the plates 18 and 19 to clear the spindle 9 the counter-punch 10 and the cop 8, they are formed with cut-out portions 30.

To one end of the shaft 17 a ratchet disk 31 is secured which is engaged by a spring pressed roller 32 carried by an arm 33 pivotally mounted at 26, and between the arms 25 and 33 there is a spring 35 yieldingly holding the roller in engagement with the ratchet disk, the said roller being adapted yieldingly to hold the disks 14 and 15 in position. To the opposite end of the shaft 17 a hand disk 36 is secured by means of which the disks 14 and 15 may be rotated.

On a pivot bolt 37 fixed to the transverse member 2 a pawl 38 is mounted which is adapted to engage the ratchet disk 31 whenever the carrier with its disks 14, 15 is lifted, for advancing the disks 14, 15 one step and setting a tube 7 into position for engagement with the spindle 9 and the counter-punch 10. The said pawl 38 is provided with a weighted arm 39 bearing on a lug 40 of the transverse member 2.

On the bearing member 20 a bell-crank lever is pivotally mounted the upwardly directed arm 41 of which provides a support for a tray or gutter 42 extending lengthwise of and above the carrier 14, 15, 18, 19, and to the other arm 43 of the said bell-crank lever a link 44 is connected which is jointed to the transverse bar 5 at 45. The dimensions of the arm 43 and the link 44 and the position of the pivot bolt 45 relatively to the carrier 14, 15, 18, 19 are such that in the lower position of the carrier 14, 15, 18, 19 the tray 42 is vertically below the spindle 9 and the counter-punch 10 so that it receives the cop from the spindle 9 and the counter-punch 10, when the counter-punch is shifted to the right, and when the said carrier 14, 15, 18, 19 is moved upwardly the tray is shifted to the right and into the position shown in Fig. 1 in dotted lines in which the cop previously taken from the spindle 9 and the counter-punch 10 is delivered to a suitable container. By means of the set screw 29 the member 20 is set into the position in which the tray 42 is exactly below the spindle 9 and the counter-punch 10.

The operation of the apparatus is as follows: After a cop 8 has been formed on a cop tube 7 the counter-punch 10 is retracted, whereupon the cop 8 drops into the tray 42. Now the cam 50 is rotated anti-clockwise in Fig. 2, whereby the carrier 14, 15, 18, 19 is lifted. By such upward movement the tray 42 is moved into the position shown in Fig. 1 in dotted lines through the intermediary of the link 44 and the arm 43, and the cop is delivered into the said container. Near the end of the upward movement of the carrier 14, 15, 18, 19 the pawl 38 engages the ratchet disk 31 and turns the disks 14 and 15 one step and into the position in which a tube 7 is below the axis of the spindle 9 and the counter-punch 10. At the end of the upward movement of the carrier the tube 7 is located between the spindle 9 and the counter-punch 10. The upward movement of the plates 18 and 19 is possible by reason of the cut-out portions 30. Now the counter-punch 10 is shifted to the left so as to clamp the said tube 7 between the same and the spindle 9. Upon further movement of the cam 50 the carrier 14, 15, 18, 19 moves downwardly by grav-

ity, and the tray 42 is returned into the position shown in Fig. 1 in dotted lines.

It will be understood that the thread of the cop is cut before the counter-punch 10 is moved to the right. Such mechanism is known in the art and I deem it not necessary to describe the same in detail.

From the foregoing description of the invention it will be understood that no guiding members or clamps or other holding devices are necessary for holding and releasing the empty cop tubes on the disks 14, 15. The uppermost cop tube is freely supported by gravity in the cut-out portions of the said disks, and the other cop tubes are held within the said cut-out portions by means of the plates 18 and 19 and their flanges 24.

By means of the hand disk 36 the disks 14 and 15 may be rotated by hand while the winding is in progress of the thread upon the cop that is in position between spindle 9 and counter-punch 10, and thus empty tubes may be placed into the frame 14, 15.

While in describing the invention reference 25 has been made to a particular example embodying the same, I wish it to be understood that my invention is not limited to the construction shown in the drawings, and that various changes 30 may be made in the general arrangement of the frame and the construction of its parts. For example, my invention is not limited to the construction in which the tray 42 is mounted on the bearing member 20. In lieu thereof the pivot of the lever 41 may be separate from the said bearing member and it may be located, for example, laterally of the axis of the disks 14, 15. In this case the lever 41 may be locked by a suitable stop in the position in which the tray is in position for receiving a cop, a spring being provided for holding the lever in engagement with the said stop.

In the figures I have shown only one cop tube and doffing apparatus. But it will be understood that a plurality of cop tubes and doffing 45 mechanisms are provided in the machine. The cam 50 is rotated for operating the doffing mechanism whenever a cop has been completed.

I claim:

1. In a cop frame the combination with means 50 for supporting a cop tube in winding position, of a rotary carrier adapted to sustain around its periphery a plurality of cop tubes, the said carrier being adapted to be moved to and from a position with one of the sustained cop tubes in alignment with said cop-supporting means, and means for rotating said carrier, whereby on successive movements of the carrier successive carrier-borne cop tubes come to alignment with said cop-supporting means.

2. In a cop frame, the combination with means for supporting a cop tube in winding position, of a carrier comprising a pair of disks borne by a

55 rotary shaft and formed about their circumferences with cut-out portions adapted to have cop tubes placed therein, stationary plates near and at the outer sides of said disks in positions for bounding the cop tubes in positions on said disks and formed each with a cut-out portion with

65 which successive pairs of cut-out portions of said disks may come to alignment, means for moving said carrier with a cop tube in alignment with said cut-out portions in the plates into position for being taken up by said cop tube supporting 70 means, and means for intermittently turning said 75

disks with the successive cop tubes into alignment with said cut-out portions of said plates.

3. In a cop frame as claimed in claim 2, the herein described improvement which consists in the said plates being formed with inwardly directed flanges adapted to engage said tubes at their ends and to hold the same in position within said cut-out portions of the disks.

4. In a cop frame as claimed in claim 1, together with means for rotating said carrier, such means consisting of, a ratchet disk connected with said carrier, and a pawl in position for engaging said ratchet disk when the carrier is being moved towards said cop tube supporting means.

5. In a cop frame as claimed in claim 1, together with means for rotating said carrier, such means consisting of, a ratchet disk connected with said carrier, a locking member yieldingly engaging said ratchet disk for yieldingly holding the same in position, and a pawl in position for engaging said ratchet disk when the carrier is being moved towards said cop tube supporting means.

6. In a cop frame as claimed in claim 2, together with a hand disk secured to the shaft of said rotary carrier for operation thereof by hand.

7. In a cop frame the combination with means

for supporting a cop tube in winding position, of a carrier adapted to bear a plurality of cop tubes mounted below the said supporting means, means for moving said carrier into and out of position with one of the cop tubes carried thereby into position for being taken up by said cop supporting means and a tray movable into and out of position for receiving a cop from said cop-tube supporting means.

8. In a cop frame as claimed in claim 1, the improvement herein described which consists in cop-removing means in the form of a tray mounted for being moved into and out of position for receiving a cop from said cop tube supporting means, the tray being movable in response to movement of the said carrier into and out of position for receiving a cop.

9. A cop frame as claimed in claim 1, together with cop removing means in the form of a tray borne by an arm pivotally mounted coaxially with said cop tube carrier, and means for swinging said arm in response to movement of said carrier into and out of position for receiving a cop from said cop tube supporting means.
